(57) **CLAIM**

The ornamental design for a foldable animal sustenance
receptacle, as shown and described.

DESCRIPTION

FIG. 1 is an isometric view of a foldable animal sustenance
receptacle showing my new design in an open configuration.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is an isometric view of a foldable animal sustenance
receptacle shown in a folded configuration.

FIG. 9 is a folded front elevation view thereof.

FIG. 10 is a folded top plan view thereof.

(Continued)

FIG. 10 is a folded rear elevation view thereof; and, FIG. 11 is a folded right side elevation view thereof. The illustrative broken line showing of bowls throughout the drawing figures depicts exemplary components which might be used with the foldable animal sustenance receptacle and forms no part of the claimed design.
